UNITED STATES PATENT OFFICE.

CHARLES K. HUTHSING, OF ST. LOUIS, MISSOURI.

FIRE EXTINGUISHER.

Application filed March 12, 1923. Serial No. 624,500.

This invention relates to fire extinguishers of the type that consist of a large container filled with a solution and a small receptacle in said container filled with a substance that is adapted to be mixed with the solution in said container so as to produce a fire extinguishing compound, the small receptacle usually consisting of a bottle arranged in a cage in the upper end of the container and provided with a "stopple" or loose cover that can be displaced or moved into an operative position so as to permit the escape of the contents of said bottle by inverting the container.

The object of my invention is to provide a fire extinguisher of the general type referred to, which is so constructed that it is impossible for the liquid in the container to splash upwardly into the discharge opening in the upper end portion of the container and leak out of the discharge hose when the container is arranged in its normal upright position.

Figure 1 of the drawings is a vertical sectional view of a fire extinguisher constructed in accordance with my invention, showing the container arranged in its normal upright position.

Figure 2 is a vertical sectional view, showing the container inverted and the "stopple" arranged in its operative position; and

Figure 3 is a horizontal sectional view, taken on the line 3—3 of Figure 1, looking in the direction indicated by the arrows.

Referring to the drawings which illustrate the preferred form of my invention, A designates a container of conventional form that is adapted to be filled with a liquid, usually a bicarbonate solution, and B designates a bottle arranged inside of said container and adapted to contain sulphuric acid, or some other substance, which, upon being mixed with the solution in the container A, will produce a fire extinguishing compound.

The bottle B is supported by a cage C arranged adjacent the upper end of the container A, and the bottle B is provided with a "stopple" or closure D composed of a horizontally-disposed top portion 1, a depending skirt portion 2 of tubular form that surrounds the neck α of the bottle and a guide 3 that projects downwardly from the top portion 1 into the neck of the bottle, as shown in Figure 1. The top portion 1 of the "stopple" is preferably of disk shape in

general outline and is of such diameter with relation to the cage C that the peripheral edge of same cooperates with the vertically-disposed side pieces γ at the upper end of the bottle cage C to hold the stopple in proper position, in the event the "stopple" is thrown upwardly from its normal seat on the rim at the upper edge of the neck of the bottle, due to a violent movement of the container A. The depending skirt portion 2 of the "stopple" is preferably so proportioned that the lower edge of same normally bears upon or contacts with the body portion of the bottle, and said skirt portion is provided at its lower end with a weight 2^a formed by a thickened portion at the lower end of said skirt that tends to hold the "stopple" in operative position on the neck of the bottle, as shown in Figure 1.

When the container A is inverted, as shown in Figure 2, so as to cause the contents of the bottle B to mix with the solution in the container A, the "stopple" D will move downwardly into an operative position without liability of jamming or assuming an angular position, due to the fact that the peripheral edge of the top portion 1 of the "stopple" slides upon and is guided by the vertically-disposed pieces γ of the bottle cage.

As shown in Figure 1, the container A is provided adjacent its upper end with a discharge opening 4 with which a discharge hose E communicates. In order to eliminate the possibility of the liquid in the container A splashing upwardly into the discharge opening 4, and thus eventually leaking out of the lower end of the hose E, I arrange a plurality of baffles F and G over the discharge opening 4, as shown in Figure 1. The baffle F, which I will refer to as the inner baffle, consists of a concavo-convex member of oval shape in general outline connected to the inner side of the top of the container at such a point that it extends over the discharge opening 4 in said top and provided with a relatively large outlet hole 5 and a plurality of drain holes 6. The cross-sectional area of the outlet hole 5 is equal to or in excess of the cross-sectional area of the discharge hole 4, and said baffle F is so positioned that the outlet hole 5 therein is disposed oppositely to a solid portion of the top of the container, and the drain holes 6 in said baffle are located at the low point of the baffle.

The baffle G, which I will refer to as the outside baffle, extends over the baffle F and is substantially L-shaped in transverse cross section, said outside baffle being considerably longer than the inside baffle, as shown in Figure 3. The upright portion or vertically-disposed portion of the baffle G is provided with two sets of orifices 7, the combined cross-sectional area of which is equal to or exceeds the cross-sectional area of the outlet hole 5 in the inside baffle, and the horizontal leg or portion of said baffle G is inclined downwardly and provided adjacent its upper and lower ends with drain holes 8. As shown in Figure 3, the orifices 7 in the baffle G are disposed oppositely to solid portions of the top of the liquid container at opposite sides of the outlet hole 5 in the inner baffle F.

If the container A is subjected to such action as to cause the liquid in same to splash upwardly against the underside of the top of said container, some of said liquid will pass through the orifices 7 in the baffle G into the space between said baffle and the top of the container, but as said orifices are located directly opposite solid portions of the top of the container, such liquid will strike against the said top, and thence fall downwardly onto the inclined lower portion of the baffle G, down which said liquid flows to the drain holes 8 and escapes through said holes back into the container A. If some of the liquid which passes inwardly through the orifices in the baffle G should enter the outlet hole 5 in the inner baffle F, such liquid will strike against the top of the container and be deflected downwardly towards the drain holes 6 at the lower end of the baffle F, due to the fact that the outlet hole 5 in the baffle F is located diametrically opposite a solid portion of the top of the container. It will thus be seen that violent agitation of the liquid in the container A cannot result in said liquid splashing out of the discharge opening 4 in the top of the container, and thus eventually finding its way to the lower end of the discharge hose E, due to the fact that said discharge opening is protected by two superimposed baffles spaced apart and provided with holes or orifices which are so positioned that each hole or group of holes is located diametrically opposite a solid wall that deflects down- wardly any liquid that passes through said opening and strikes against said wall, the baffles having drain openings so as to permit the escape of any liquid that passes through said baffles. When the container is inverted the contents of same can escape freely through the hose E, due to the fact that the cross-sectional area of the orifices 7 in the baffle G and of the outlet hole 5 in the baffle F are equal to or in excess of the cross-sectional area of the discharge opening 4 in the top of the container.

Having thus described my invention, what I claim as new and desire to secure by Letters Patent is:

1. A fire extinguisher, comprising a liquid container that is adapted to be inverted to discharge the contents of same, a discharge opening in the top of said container, a substantially concavo-convex baffle connected to the inner side of said top over said discharge opening and provided with an outlet hole disposed out of alignment with said discharge opening, and a second baffle connected to the inside of the top of the container and arranged over the baffle first referred to, said second baffle having orifices disposed oppositely to solid portions of the top of said container. 70
2. A fire extinguisher, comprising a liquid container adapted to be inverted so as to discharge the contents of same, a discharge opening in the top of said container, a substantially concavo-convex, oval-shaped baffle connected to the inner side of said top and extending over said discharge opening, said baffle having an outlet hole disposed oppositely to a solid portion of said top and drain holes arranged adjacent its lower end, a second baffle of substantially angle shape in cross section connected to the inner side of the top of the container and arranged over the baffle first referred to, sets of orifices in the vertical leg of said angle-shaped baffle disposed oppositely to solid portions of the top of the container, and drain holes in the horizontal leg of said angle-shaped baffle. 75
3. An outlet guard for liquid receptacles, comprising a baffle plate positioned in front of the outlet, and a perforated guard plate positioned in front of the baffle plate and spaced therefrom. 80
